(57) CLAIM

The ornamental design for media player, as shown and described.

DESCRIPTION

FIG. 1 is a front view of a media player showing our new design.

FIG. 2 is a back view thereof.

FIG. 3 is a bottom view thereof.

FIG. 4 is a top view thereof.

FIG. 5 is a left side view thereof, the right side view being a mirror image thereof; and,

FIG. 6 is a perspective view thereof.

The broken lines are for illustrative purpose only and form no part form the claimed design.

1 Claim, 4 Drawing Sheets

FIG. 1

FIG. 2

FIG. 3

FIG. 4

FIG. 5

FIG. 6
